UNITED STATES PATENT OFFICE.

ANDREW S. HOKANSON, OF SEEKONK, MASSACHUSETTS.

DESIGN FOR A WATCH-FOB.

56,874.

Specification for Design.

Patented Jan. 4, 1921.

Application filed June 10, 1919. Serial No. 303,244. Term of patent 7 years.

To all whom it may concern:

Be it known that I, ANDREW S. HOKANSON, a citizen of the United States, residing at Seekonk, county of Bristol, and State of Massachusetts, have invented a new, original, and ornamental Design for a Watch-Fob, of which the following is a specification, reference being had to the accompanying drawing, forming part hereof.

Figure 1 is a face view and Fig. 2 is an edge view of a watch fob, illustrating my new design.

I claim:

The ornamental design for a watch fob, as shown.

ANDREW S. HOKANSON.
